CLAIM

We claim the ornamental design for a luminaire, as shown and described.

DESCRIPTION

FIG. 1 is a first perspective view of a reflector of a luminaire according to a new design.

FIG. 2 is a second perspective view of the reflector of FIG. 1.

FIG. 3 is a third perspective view of the reflector of FIG. 1.

FIG. 4 is a first side elevation view of the reflector of FIG. 1.

FIG. 5 is a second side elevation view of the reflector of FIG. 1.

FIG. 6 is a third side elevation view of the reflector of FIG. 1.

FIG. 7 is a fourth side elevation view of the reflector of FIG. 1.

FIG. 8 is a top plan view of the reflector of FIG. 1; and, FIG. 9 is a bottom plan view of the reflector of FIG. 1.

The elements shown in broken lines are included for the purpose of illustrating portions of the luminaire that form no part of the claimed design.

1 Claim, 8 Drawing Sheets
